UNITED STATES PATENT OFFICE

MARY V. NEWHouser, OF ANADARKO, OKLAHOMA

CLOTHES CAR

Application filed February 26, 1929. Serial No. 342,868.

This invention relates to vehicles and more particularly to a clothes car for home laundry use.

One of the objects of the invention is to provide, in a manner as hereinafter set forth, 5 a convenient conveyor for washed clothes in the wet state from the house to where the same are to be hung out for drying, and to further provide means for conveying all of the accessories necessary in the activities on 10 one simple and compactly arranged vehicle.

Further objects of the invention are to provide a device of the character referred to, which is light in construction, novel in its 15 method of assembly, strong, compact and durable, which is highly efficient for its intended purpose and thoroughly reliable in its use, easily operated by the housewife and comparatively inexpensive to manufacture 20 and assemble.

With the foregoing and other objects in view, the invention consists in the novel construction, combination and arrangement of parts as hereinafter more specifically described and illustrated in the accompanying drawings, but it is to be understood that changes, variations and modifications may be resorted to without departing from the spirit of the claims hereunto appended.

30 In the drawings wherein like reference characters designate corresponding parts throughout the several views:

Figure 1 is a side elevation of the device in accordance with this invention, illustrating the method of utilizing the device for carrying a clothes basket or other receptacle,

Figure 2 is a top plan view of the device in accordance with this invention,

Figure 3 is a central, detailed, longitudinal, 40 vertical section of the device taken on line 3—3 of Figure 2,

Figure 4 is a vertical, transverse section taken substantially on line 4—4 of Figure 3.

Referring to the drawings in detail, the 45 laundry cart in accordance with this invention comprises an open substantially rectangular body portion indicated generally at 5 having a rectangular open top casing or clothes receptacle 6 detachably confined 50 within the body portion 5. The body portion

5 is formed of unitary side frames 7, 8 secured together in spaced relation by transversely extending end rails 9, 10 at the upper forward end and the upper rear end of the frames.

The side frames 7, 8 are braced by diagonally extending cross trusses 11, 12 secured to the alternate interior corners of each frame to provide reinforcements for the said side frames.

The bottom 13 of each side frame is up-set 60 with respect to the lower end of the end rails 14, 15 forming integral angularly disposed axle supporting brackets 16, 17 where the bottom and respective sides merge with each other. The pairs of angularly disposed axle 65 brackets on the side frames have transverse axles 18, 19 coupled thereto on the opposite free ends of which are rotatably mounted pairs of wheels 20, 21. The axles are stationary with respect to the body portion.

A substantially elongated flattened strap 70 is secured to the ends 14, 15 of the side frames 7, 8 adjacent the bottom thereof and said strap 22 is formed in an integral forwardly 75 directed loop 23 intermediate the two forward ends 14 of each side frame.

It will be clearly understood by reference to the drawings that the strap 22 is coextensive with the two side frames and the forward end of the body portion and is formed 80 of a single piece of metal.

The forwardly directed loop 23 forms a bottom support for the bottom of the open top semi-cylindrical clothes pin container 24, 85 the upper end of which is supported in the loop 25 and the ends of the loop 25 are secured to the forward transverse end rail 9. The loop 23 extends forwardly in the same plane as the strap 22 and the loop 25 extends 90 forwardly in the same plane as the end rail 9.

A plurality of transversely extending substantially U-shaped cross bars indicated generally at 26 have their opposite legs 27, 28 secured to the strap 22 by means of the hold fast devices 29' and the bight portions 29 of the cross bars are disposed between the opposite side frames 7, 8. The plurality of cross bars 26 are longitudinally spaced from each other and have the bight portions 29 disposed 100

in the same plane to form a cradle at the bottom of the body portion 5 to provide supports for the longitudinally extending bars to be presently described.

5 A plurality of longitudinally extending transversely spaced, substantially yoke-shaped bars indicated generally at 30 have the ends of the legs 31 of each bar coupled to the transversely extending axles 19, 20 and the bight portion 32 of each bar rests upon and is supported by the plurality of transversely extending bight portions 29 of the respective cross bars, 26.

10 The bottom 33 of the container 6 rests upon the bight portions of the longitudinally extending bars 30 and the sides 34, 35 thereof are slidably disposed between the spaced unitary side frames 7, 8.

15 Longitudinally extending transversely spaced slats 36, 37 are fixed to the top of the body portion 5 by having the opposite ends 38, 39 of each slat secured to the forward and rear end rails 9, 10, respectively. Intermediate the ends 38, 39 each slat is supported in abutting relation to a strut 40 which is secured at its opposite ends to the upper rail of the side frames 7, 8 as at 41, 42.

20 Strut 40 provides a bracing means between the ends of the slats 36, 37 so as to support a dry clothes can receptacle 43 on the top of the body portion 5 without warping or otherwise injuring the body portion.

25 Hingedly mounted upon the opposite bottoms 13 of the side frames 7, 8 are a pair of angular shaped clamps 44 having the free legs 45 in abutment with the lower end of the rear wall 46 of the clothes receptacle 6 for the purpose of detachably confining the said receptacle within the substantially open body portion 5.

30 A handle 46' is secured to the upper end of the rear wall 46 for the purpose of facilitating the withdrawal of the receptacle, while a pair of handles 47, 48 are secured to the rear end rail 15 of each side frame to push the laundry car about the yard.

35 Owing to the reinforcing and unitary structure of the various parts of the clothes car, the parts thereof may be formed of very light steel or in case of the desirability of a very light body portion aluminum parts may be used.

40 Inasmuch as the clothes car is to be used by a housewife of limited strength, it is desirable and even imperative that the vehicle be constructed as light as possible. The clothes pin receptacle 24 and the clothes receptacle 6 may be formed of aluminum or very light galvanized iron so as to promote lightness in structure.

45 A novel assembly of parts is embodied in the foregoing structure and an explanation thereof will make it clear to those skilled in the art.

50 In the assembly of the clothes car in ac-

cordance with this invention, the side frames 7, 8 with the diagonal braces 11, 12 may be formed as an integral unit and purchased in large quantities from the metal market and it is furthermore pointed out that the strap 22 with the cross bars 26 may be fabricated as a unit.

55 Since the cradle formed by the strap and cross pieces 26 overlaps the bottom 13, said cradle may be placed on the floor, and the side frame inserted therein and secured thereto either by welding or riveting. The longitudinal bars 30 may then be assembled in the proper relation and the respective axles 18, 19 inserted and slid therethrough.

60 All that is left to be done in the assembly is the insertion and fixing of the end rails 9, 10 with the strut 40 and the slats 36 and 37 secured thereto. It is pointed out that the end rails 9, 10 with the slats secured thereto, together with the strut 40 may be assembled and inserted as a unitary structure which may be fabricated and purchased in large quantities.

65 It is believed that the foregoing description of the assembly of parts will be clearly understood by those skilled in the art and the same promotes a novel method of assembly which is one of the objects of this invention.

70 What I claim as new is:

1. In a clothes car of the character described comprising a receptacle confining body portion of substantially rectangular configuration, a receptacle detachably confined within said body portion, said body portion formed of a pair of unitary side frames of substantially rectangular contour secured together at their opposite upper ends by a pair of transversely extending end rails, and said side frames secured together adjacent the bottoms thereof by a strap co-extensive with said frames and the forward end of said body portion, a plurality of spaced, transversely extending, substantially U-shaped cross bars secured to the sides of the strap to form a cradle for reinforcing the bottom of said body portion, the bottoms of said pair of side frames being upset with respect to the lower extremities of the ends thereof to form angularly disposed axle supporting brackets integral with said side frames at the opposite ends thereof, and a pair of axles extending transversely of and rigidly secured to adjacent axle brackets at the opposite ends of said frames, a pair of wheels journaled on the free ends of each axle laterally of said side frames, a plurality of longitudinally extending, substantially yoke-shaped spaced bars having the opposite legs thereof rigidly supported on said axles and the bight portions thereof supported on the cross bars of said cradle, and a plurality of longitudinally extending spaced slats secured to and extending between said end rails to provide a support for a second receptacle.

2. In a clothes car of the character described comprising a receptacle confining body portion of substantially rectangular configuration, a receptacle detachably confined within said body portion, said body portion formed of a pair of unitary side frames of substantially rectangular contour secured together at their opposite upper ends by a pair of transversely extending end rails, and said side frames secured together adjacent the bottoms thereof by a strap co-extensive with said frames and the forward end of said body portion, a plurality of spaced, transversely extending, substantially U-shaped cross bars secured to the sides of the strap to form a cradle for reinforcing the bottom of said body portion, the bottoms of said pair of side frames being upset with respect to the lower extremities of the ends thereof to form angularly disposed axle supporting brackets integral with said side frames at the opposite ends thereof, and a pair of axles extending transversely of and rigidly secured to adjacent axle brackets at the opposite ends of said frames, a pair of wheels journaled on the free ends of each axle laterally of said side frames, a plurality of longitudinally extending, substantially yoke-shaped spaced bars having the opposite legs thereof rigidly supported on said axles and the bight portions thereof supported on the cross bars of said cradle, and a plurality of longitudinally extending spaced slats secured to and extending between said end rails to provide a support for a second receptacle, said strap formed with an integral forwardly directed loop in the same plane as the strap on the forward end of said body portion, a forwardly directed loop secured to the forward end rail and a clothes pin receptacle supported within said loop, a pair of hinged clamps secured to said side frames having the ends thereof frictionally engaging with said receptacle for detachably confining said receptacle within said body portion.
3. In a clothes car of the character described comprising a receptacle confining body portion of substantially rectangular configuration, a receptacle detachably confined within said body portion, said body portion formed of a pair of unitary side frames of substantially rectangular contour secured together at their opposite upper ends by a pair of transversely extending end rails, and said side frames secured together adjacent the bottoms thereof by a strap co-extensive with said frames and the forward end of said body portion, a plurality of spaced, transversely extending, substantially U-shaped cross bars secured to the sides of the strap to form a cradle for reinforcing the bottom of said body portion, the bottoms of said pair of side frames being upset with respect to the lower extremities of the ends thereof to form angularly disposed axle supporting brackets integral with said side frames at the opposite ends thereof, and a pair of axles extending transversely of and rigidly secured to adjacent axle brackets at

the opposite ends of said frames, a pair of wheels journaled on the free ends of each axle laterally of said side frames, a plurality of longitudinally extending, substantially yoke-shaped spaced bars having the opposite legs thereof rigidly supported on said axles and the bight portions thereof supported on the cross bars of said cradle, and a plurality of longitudinally extending spaced slats secured to and extending between said end rails to provide a support for a second receptacle, said strap formed with an integral forwardly directed loop in the same plane as the strap on the forward end of said body portion, a forwardly directed loop secured to the forward end rail and a clothes pin receptacle supported within said loop, a pair of hinged clamps secured to said side frames having the ends thereof frictionally engaging with said receptacle for detachably confining said receptacle within said body portion.

In testimony whereof I affix my signature.

MARY V. NEWHouser.
